United States Patent Office

Des. 191,002
Patented Aug. 1, 1961

191,002

CLOCK

Rudolph Axelrod, 280 Fort Washington Ave.,
New York, N.Y.

Filed Jan. 24, 1961, Ser. No. 63,680

Term of patent 7 years

(Cl. D42—7)

FIG. 1.

FIG. 1 is a front elevational view of a clock, showing my new design;

FIG. 2 is a rear elevational view thereof; and

FIG. 3 is a sectional view taken on the line 3—3 of FIG. 1.

I claim:

The ornamental design for a clock, substantially as shown.
